Inventor
Charles D. Bonsall
Gantow, Tessison,
Attorney

Patented Nov. 20, 1928.

UNITED STATES PATENT OFFICE.

CHARLES DAVID BONNALL, OF NEW KENSINGTON, PENNSYLVANIA.

LOAD-LIFTING ARRANGEMENT.

Application filed November 12, 1926. Serial No. 147,989.

The device relates to railway freight cars and comprises means which reinforce the roof structure and provides places for attaching load lifting devices, such load lifting devices being used to move heavy articles into and out of the car or to move such articles within the car or to place one part of the load over another part, such as double decking automobiles.

An object of the invention is to provide a longitudinally extending load lifting beam which cooperates with the usual ridge pole of a car so that each reinforces the other, i. e., the load lifting beam strengthens the ridge pole to resist the weaving stresses of the car and supports the roofing and also the ridge pole assists the load lifting beam in sustaining the weight of the load being lifted.

Another object of the invention is to attach the beam to the ridge pole between the carlines, as well as at the carlines, so as to shorten the span of the load lifting beam between its supports.

By arranging these elements to coact with each other their size and strength may each be reduced, thereby reducing their weight and cost.

In the drawings:

Fig. 1 shows a lateral cross section of part 30 of a railway car with my device applied thereon.

Fig. 2 shows a longitudinal cross section of part of a railway car with my device applied thereon on 2-2 of Fig. 1.

Fig. 3 is a section on line 3-3 of Fig. 2.

Figs. 4 and 5 show the relation of the beam and ridge pole at the carline of a modified form.

Figs. 6 and 7 show a modified form of attachment of the beam to the ridge pole between the carlines.

The usual parts of the car are shown wherein 1 is side plate; 2 the end plate; 3 the carline; 4 the ridge pole; 5 the roof sheet; 6 the transverse cap; 7 the running boards and 10 the purlins. The carlines 3 span the distance between the opposite side plates 1 and are attached thereto in any convenient manner, and the ridge pole 4 extends longitudinally of the car and is attached to the carlines 3 and end plate 2 so as to brace the roof structure and also support the roofing

5. In ordinary construction the roof sheets or other roofing rests upon the side plates, purlins and ridge pole. 55

My device comprises a longitudinally extending load lifting beam 8 which preferably extends the full length of the car and has its opposite ends secured to the end plates 2, thus increasing its range of operation. 60 This beam is positioned below the ridge pole 4 (or purlin 10) and spaced apart from it so as to provide a space 9 for the insertion of the rope or chain of a load lifting device or a hook or ice tong. The load lifting beam 65 may be attached directly to the carline, as shown in Fig. 4, or may be attached to the carline and ridge pole, as shown in Fig. 2. Filler blocks 11-11 may be used between the ridge pole and the beam which may be 70 tapped into these members if desired. The load lifting beam is attached to the ridge pole between the carlines but the means of attachment only partially closes the space 9 between the beam and ridge pole. The means 75 of attachment, such as bolt (or bolts) 12 causes the beam and pole to act in unison to resist the weaving of the car, and, furthermore, any load sustained by the load lifting beam is partially transmitted to the ridge 80 pole and also the beam helps the ridge pole sustain the roof or any load therein.

Figs. 4 to 7 inclusive show modified forms wherein the load lifting beam 8 is attached directly to the carline 3 and the attachment 85 13 of the beam to the pole, between the carlines, is such that the beam and attachment may be removed or replaced without disturbing the roofing by simply removing the bolt 14. 90

My construction may be used in combination with either a purlin, ridge pole or other longitudinally extending frame member.

The accompanying drawings illustrate the preferred form of the invention, though it is 95 to be understood that the invention is not limited to the exact details of construction shown and described, as it is obvious that various modifications thereof within the scope of the claims will occur to persons skilled in 100 the art.

I claim:

1. In a railway car, the combination of a plurality of carlines, a longitudinally extend-

ing frame member, a load lifting beam positioned below said member and spaced apart therefrom, fillers between the member and beam between the carlines secured to the member and the beam, and other fillers between the member and beam below the carlines secured to the member and the beam.

5 2. In a railway car, the combination of a

plurality of carlines, a longitudinally extending frame member, a load lifting beam positioned below said member and spaced apart therefrom, and means for attaching said beam to said member comprising a bracket secured to the beam and a horizontal bolt securing said bracket to said member.

CHARLES DAVID BONSALL.
